UNITED STATES PATENT OFFICE

2,014,693

PLUNGER OPERATED TONGS

Olof Ohlson, Newton, Mass., assignor to Ohlson Metal Products Company, Newton, Mass., a corporation of Massachusetts

Application January 13, 1934, Serial No. 706,454

6 Claims. (Cl. 294—115)

The form of the present invention herein presented for illustration is designed for handling ice cubes at the dining table, wherefore its jaws are given a spread and arc of movement sufficient to embrace and grip ice cubes of the dimensions which are produced by the generally used makes of domestic mechanical refrigerator. The principles of the invention are, however, obviously applicable to tongs of larger or smaller dimensions, for instance, sugar tongs, wherefore this illustration is not to be construed as a limitation of the invention in respect to dimensions, proportions and possible uses.

My object is to provide tongs of the plunger operated type having novel features of construction by which the structure is rendered more compact than tongs of similar types heretofore devised, the operation of the moving and actuating parts is made more efficient, and manufacture at minimum cost is made possible. The particulars in which the invention consists are described in the following specification and more particularly pointed out in the claims.

In the illustrative drawing herewith,—

Fig. 1 is an elevation of the tongs with the shank partly broken away to show the interior plunger;

Fig. 2 is an elevation of the tongs as viewed from the right hand side of Fig. 1;

Fig. 3 is a partial section taken on line 3—3 of Fig. 2;

Fig. 4 is a view like Fig. 3 except that the jaws are shown in closed position with the actuator similarly placed;

Fig. 5 is a plan as seen from a viewpoint above the position of Fig. 1;

Figs. 6 and 7 are cross sections taken on lines 6—6 and 7—7 respectively of Fig. 1;

Fig. 8 is a perspective view of disassembled parts of the tongs.

Like reference characters designate the same parts wherever they occur in all the figures.

The main parts of the tongs are a shank 10 to which two jaws 11 and 12 are pivoted by a pivot stud 13, and a plunger 14 which protrudes at one end from the shank and at its other end is coupled to the jaws by means later described. The shank carries at the end remote from the jaws a cross bar, or equivalent member which provides abutments 15 and 16 adapted to be embraced by two fingers of the hand while a knob 17 on the extremity of the plunger is pressed upon by the thumb or the heel part of the hand.

Turning now to the details of construction, the shank is made of tubing, preferably in two sec-

tions; one of which, extending from the cross bar 15—16 to the ferrule 18, is cylindrical, and the other of which, shown in Figs. 3, 4 and 8 and designated 19, is square in cross section. The square section is approximately equal in both width dimensions to the bore of the tubular section and its corners are cut away for a short distance adjacent to one end, as shown in Fig. 8 so that the extensions of its sides then remaining are enabled to pass into the adjacent end of the 10 cylindrical section and to fit closely enough therein to be securely attachable by solder. The ferrule 18 surrounds the same part of the square section and has a flange enveloping the tubular section. It also is secured by solder. The other 15 end of the square section is cut through at two opposite sides so as to form tongues 20 which are bent in toward one another and provide an abutment for the spring 21. The intermediate sides are left intact and provide lugs 22 which are perforated to receive the pivot stud 13 and between which the butt ends of the jaws are received. In two opposite sides of the section 19, which may be either pair of sides, are slots 23 to accommodate a coupling pin 24.

A coupling sleeve 25 which is a section of tubing sufficiently large to have a free sliding fit on the square shank section 19, is placed on the latter and is connected with the plunger 14 by the pin 24 last mentioned. This sleeve is provided with prongs or lugs 26 at its four corners, the extremities of which are curled over making eyes 27 for reception of the pins 28, 29, by which the jaws 11 and 12 respectively are coupled to the sleeve. The butt end of jaw 11 is mounted 30 in the space 30 between one pair of aligned eyes and the jaw 12 is similarly mounted between the eyes of the other pair. The sides of the sleeve intermediate both pairs of eyes are notched as at 31 to accommodate the pivot 13. 40

Pins 28 and 29 pass through slots 32 and 33 in the respective jaws and preferably are equipped with anti-friction rollers in those parts which occupy the slots. A sufficient range of plunger movement is provided, and the slots 32 and 33 45 are suitably disposed, to effect movement of the jaws from the wide open position of Figs. 1 and 3 to the closed position of Fig. 4.

Spring 21 being under compression between the abutment 20 and the adjacent end of plunger 14 50 thrusts the plunger outward and normally holds the jaws in the open position. Their limits of outward movement are established by shoulders 34 on them which abut against the contiguous sides of the shank section 19, as shown in Fig. 3; 55

the spaces 30 in the coupling sleeve being made deep enough to permit this effect.

The jaw construction which I am now about to describe is a feature of the invention. Each 5 jaw is made of two pieces, designated distinctively as 11, 11a and 12, 12a, in the drawing. These four pieces are preferably made as stampings from sheet metal, and are duplicates of one another. The pieces 11 and 11a which make the 10 jaw 11 are soldered together at the tip of the jaw; and the pieces 12 and 12a are similarly soldered together. The shaded areas shown at 35 and 35 in Figs. 3 and 4 indicate in a general way the locations where the solder is applied. These pieces 15 are so joined to one another as to be divergent away from the tips, whereby they are separated by a space of considerable width at the butts of the jaws, as appears from Figs. 2 and 5. When free and unconfined, the spread between them is 20 wider than that shown in these figures; which means that in being assembled with the shank the side pieces of the jaws must be squeezed in toward one another, and after being released they spread apart and press outwardly against the 25 holding lugs 22. There is sufficient elasticity and resilience in the material of which the jaw pieces are made to cause them thus to expand and to bear with considerable pressure against these lugs. By this means the jaws are centered and fitted 30 to the holder without backlash and without necessity of making the space between the lugs exactly equal to the thickness of the material parts of the jaws. This is a factor of practical importance from the point of view of manufacturing facility and cost.

In assembling the jaws they are preferably interleaved, being thus symmetrically arranged and their side pieces being put under equal stress. To accommodate this arrangement the spaces 30 40 in the coupling sleeve between the two alined eyes 27 of each pair are set off center by substantially the thickness of one of the jaw pieces, being correspondingly and oppositely offset in the two opposite sides of the sleeve. These spaces 45 and the intermediate notches 31 are cut in an originally intact section of tubing by dies; and the dies are so designed as to leave strips of the metal at opposite sides of the sleeve, and flanking the notches 30, sufficiently long to be rolled up 50 and form the eyes 27.

The use of square tubing for the shank section 19 and sleeve 25, which tubing can be bought in stock sizes suitable for the uses here described, enables me to provide the fulcrum lugs 22 for the 55 jaws and the anchorages for the propelling pins 28 and 29 in suitable locations, with a minimum of machining and of operating cost. Accordingly I claim this as a factor of the invention. However, other features of invention herein claimed 60 are not necessarily limited to cooperation and combination with those details only.

What I claim and desire to secure by Letters Patent is:

1. Tongs consisting of a tubular shank having 65 separated lugs at one end, jaws pivoted between said lugs in the approximate center line of the shank, a plunger movable endwise within the shank, a coupling sleeve fitted to slide endwise on the shank externally thereof and having propelling pins at opposite sides of the fulcrum pivot, the jaws having slots in which said pins are respectively contained and being disposed to

cause closing and opening movements of the jaws by the pins with movements of the sleeve in opposite directions, and a motion transmitting connection between the plunger and sleeve.

2. Tongs comprising a shank having separated lugs protruding at one extremity, jaws arranged with their butt ends between said lugs and connected thereto by a fulcrum pivot, a sleeve fitted 10 slidily on the shank having two pairs of alined eyes arranged so that the eyes of each pair embrace one of the jaws, and pins mounted in said eyes, the jaws having slots receiving said pins and so disposed that movement of the sleeve endwise relatively to the shank causes the jaws to be spread apart and closed together respectively. 15

3. Tongs consisting of jaws each formed of similar flat pieces connected together at their tips and spread apart at their butt ends with provision for resilient flexure toward one another, a shank having separated lugs on one end between which 20 the butt ends of the jaws are contained, the space between said lugs being less than the normal outside width of the interleaved jaw butts when free from external restraint, whereby the butt ends of said jaw pieces are confined under stress by 25 the lugs when assembled between the lugs, and a fulcrum pivot connecting said lugs and overlapped jaw butts.

4. Tongs consisting of a shank having an end section with spaced apart lugs projecting from 30 the outer end thereof and inturned spring abutments between said lugs, a sleeve fitted slidily on said shank section and having spaced apart projections arranged in opposite pairs, each pair having eyes in alinement with one another, jaws 35 extending each between the eyes of one of said pairs into overlapping relationship between said lugs, a fulcrum pivot passing through said lugs and the overlapping ends of the jaws, thrust propulsion pins carried each by a pair of said alined 40 eyes, and the jaws being slotted each to receive one of said propulsion pins, a plunger slidable endwise within the shank coupled to said sleeve, and a spring reacting between the plunger and shank tending to hold the jaws in open position 45

5. Tongs consisting of a tubular shank, a plunger movable endwise within said shank, a spring reacting between the shank and plunger tending to thrust the plunger in one direction, an external sleeve fitted to slide on one end of the 50 shank, a pin connecting said sleeve and plunger, the shank having slots in its sides through which said pin passes, and tong jaws pivoted to the shank and having cam propulsion connection 55 with the sleeve.

6. Tongs comprising a shank, a plunger longitudinally movable relative to said shank, a pair of jaws pivoted centrally to the shank at one end, a spring reacting between said plunger and shank 60 tending to move the plunger away from the jaws, and coupling means between the jaws and plunger comprising a slot in each jaw extending transversely away from the center line of the shank from a point spaced outwardly from the central pivot point and located between such pivot point 65 and the extremity of the jaw, and pins occupying the slots of the respective jaws and connected with the plunger, whereby movement of the plunger toward the jaws is effective to close the 70 extremities of the latter toward one another.
